UNITED STATES PATENT OFFICE.

VICTOR E. FLODIN, OF CHICAGO, ILLINOIS, ASSIGNOR TO CRANE COMPANY, OF CHICAGO, ILLINOIS, A CORPORATION OF ILLINOIS.

DESIGN FOR A HANDWHEEL FOR A VALVE.

Application filed November 28, 1923. Serial No. 7,909. Term of patent 14 years.

To all whom it may concern:

Be it known that I, VICTOR E. FLODIN, a citizen of the United States, residing at Chicago, in the county of Cook and State of Illinois, have invented a new, original, and ornamental Design for Handwheel for Valve, of which the following is a specification, reference being had to the accompanying drawing, forming part thereof,

Fig. 1 is a plan view;

Fig. 2 is a sectional view taken on line 2—2 of Fig. 1; and

Fig. 3 is a bottom view.

I claim:

The ornamental design for a handwheel for a valve, as shown.

VICTOR E. FLODIN.
